WILLIAM TUTTLE, OF BOSTON, MASSACHUSETTS.

Letters Patent No. 83,803, dated November 3, 1868.

IMPROVED STREET-RAILWAY SWITCH.

The Schedule referred to in these Letters Patent and making part of the same.

To all persons to whom these presents may come:

Be it known that I, WILLIAM TUTTLE, of Boston, in the county of Suffolk, and State of Massachusetts, have invented an Improved Switch-Mechanism for Railway-Carriages; and I do hereby declare the same to be fully described in the following specification, and represented in the accompanying drawings, of which—

Figure 1 is a front-end view,

Figure 2, a longitudinal section, and

Figure 3, a transverse section of a railway-car provided with my invention.

Figure 4 is a top view, and

Figure 5, a transverse section of the rails of two tracks, and the deflector used at the junction of the tracks, such deflector being employed with the oscillatory shoe, to be hereinafter described, to effect the passage of a car from one to the other of the said tracks.

The purpose of the invention is to enable the car to be switched from one track upon another, or siding, and it accomplishes this by bearing against the wheel of the car, and a cam or deflector arranged on the track, and projecting above it.

I am aware that it is not new to deflect a car from one track to another by means of a cam on one track, and by an arm projecting down from the car-body, such arm being provided with means for elevating and depressing it. I am also aware that it is not new to employ a shoe pivoted to a bracket, so as to vibrate vertically. This latter arrangement will be found in the patent of Allen and Snow, dated on or about October 15, A. D. 1867. Therefore, I make no claim to such.

My invention is an improvement with reference to the said shoe; and in carrying out my improvement I so suspend the shoe, that when lowered to act against the deflector or cam of the track, and to rest directly against the inner face of the wheel to be deflected, it may have a pendulous lateral motion, and an oscillating longitudinal motion. The wheel is deflected by pressure made directly against it through the shoe, which, when in operation, rests on and is drawn over the surface of the track, and against the cam or deflector, and is free to play up and down, to rock longitudinally, as well as move laterally. This freedom of motion vertically, as well as laterally and longitudinally, prevents the shoe from being caught by any sleeper or obstruction on the track, or enables it to pass such with great ease, and still, when necessary, perform its duty of aiding in deflecting the car from one track to another.

In the drawings—

A denotes the car or truck-frame;

B B, its axles; and

C C, the wheels.

The two deflector-shoes of a pair of the wheels belonging to one axle are shown at D D'. Each is supported by a hanger, a, extended from an arm, b, which projects from a horizontal shaft, c, arranged in proper bearings applied to the truck-frame.

A handle, d, extends upward from the front end of each of the shafts c, and between stops, e f, arranged

on the dasher g, in manner as represented in the drawings. By laying hold of the handle, and moving it, the shoe may be either raised or depressed relatively to the track.

Furthermore, each of the shoes is supported by brace-chains or rods, h i, extending from its two ends, in manner as represented in the drawings, and being fastened to the carriage-frame, or a bracket, k, projecting down therefrom.

If desirable, the shoe may have friction-rollers arranged on either or both of its opposite vertical edges. So, the suspension-rod of the shoe may be arranged in a guide-tube, m, extended down from the carriage-frame, and having a bore of sufficient diameter to allow the shoe the proper lateral swing or motion. The brace-chains or rod serve to support the shoe at its ends, as well as to draw it along while in operation.

In respect to the deflector or switch U, instead of carrying the wheel-flange groove n entirely through it, I terminate it against a short inclined plane, o, which rises up to another inclined plane, p, which slopes in the opposite direction up to r, the level of the rail T. Thence there is a down slope at q. The main-track rail is shown at T T', and the siding-rail at S.

Figure 6 is a longitudinal section on the line x x, and

Figure 7, another such section, on the line x y of fig. 4.

The deflector or cam is shown at r' as rising above the plane q. On its inner side, this deflector is grooved lengthwise, as shown at s in fig. 5, the same being in order to enable the shoe, while passing along the deflector, to enter such groove, such groove serving to keep such shoe from slipping off the deflector.

The purpose of the inclined plane p, as arranged with the main-track rail T T', the siding-rail S, and the wheel-flange groove n, as shown in figs. 4, 5, and 6, and as above described, is to prevent the wheel-flange being diverted into the groove n when it may be desirable to keep the wheel on the track T T', and the wheel may be moving over the switch from T to T'.

I claim as my invention, the combination of the shoe with the car-body, by means of the links or rods a and h, when these links are connected to the said shoe and body in such manner as to permit of the shoe oscillating or moving laterally as well as vertically, so as to accommodate itself to the surfaces over, on, or against which it may pass, substantially as described.

I also claim the combination of the steadyng-tube m with the car-body, and the shoe applied thereto, substantially as described.

I also claim the arrangement and combination of the inclined planes or chutes, p and q, with the rails S T T', the flange-groove n, and the deflector r'.

I also claim the combination and arrangement of the inclined plane o, the groove n, the inclined planes or chutes p q, the rails S T T', and the deflector r'.

WM. TUTTLE.
